SKI CLAMPING DEVICE

Léandre Aubert, St. Adele, Quebec, Canada

Application June 12, 1936, Serial No. 84,972
In Canada June 13, 1935

3 Claims. (Cl. 280—11.37)

The present invention relates to devices for clamping skis.

An object of the invention is the provision of a device for holding skis in desired form.

A further object of the invention is the provision of a device designed to connect a pair of skis together and to retain them in predetermined curved arrangement.

Another object of the invention is the provision of a clamping device of the aforesaid character which is designed to enable convenient predetermined curving of the skis.

A still further object of the invention is the provision of a clamping device of the above character which may be collapsed when not in use.

Still another object of the invention is the provision of a ski clamping device of the aforesaid character which is simple and durable in construction and efficient for the purpose intended.

Other objects and advantages of the invention will become apparent as the description progresses.

In the accompanying drawing forming a part of this specification and in which like reference characters are employed to designate corresponding parts throughout the same:—

Figure 1 is a perspective view of the device in extended ski engaging assembly,

Figure 2 is a side elevational view showing a pair of skis clamped in the device,

Figure 3 is a vertical longitudinal section through the extended device, and

Figure 4 is a transverse section taken on the line 4—4 of Figure 2.

Referring to the drawing, wherein for the purpose of illustration is shown a preferred embodiment of the invention, A generally designates a longitudinal body member embodying a main centrally disposed tubular section 10. With the ends of the main section 10 are telescopically connected a pair of intermediate sections 11 slidably within the main section. To the outer ends of the intermediate sections 11 are connected a pair of telescopically engaging end tubular sections 12.

At the outer extremity of each end section 12 is formed a transversely disposed tubular cross arm 14 arranged at right angles to the sections. Adjacent the ends, the cross arm 14 is formed with a plurality of transverse apertures 15. Slidably disposed through the apertures 15 of each cross arm is a U-shaped bracket 16 formed of round bar metal having an arcuate offset 17 in the cross bar portion. The side legs of each bracket 16 are provided, at the ends, with screw threads 18

adapted to receive thereon wing nuts 19. The wing nuts 19 are disposed to adjust on the side arms of each bracket an auxiliary tubular cross arm 20 having apertures adjacent the ends through which the end portions of the cross arm legs are extended.

At the central portion of the elongated body member A is secured a transversely disposed spacing member 22, in the present instance, in the form of a flat metallic plate of elongated rectangular form having indentations 23 in the top and bottom edges.

The device is associated with a pair of skis by arranging each ski in a longitudinal position thereon, the centre of each ski being disposed in the indentation 23 in the top and bottom edges of the spacing member 22. The end portions of each ski, that is the portions at each side of the centre extend through opposite side portions of the brackets, the end portion of one ski being disposed between the cross bar 14 and the cross piece 17 of the bracket while the corresponding end portion of the opposed ski is disposed between the cross bar 14 and the auxiliary cross bar 20 at the end of the bracket. As the brackets are disposed in reverse positions the two skis are correspondingly mounted therein. After the skis have been initially positioned, the thumb-screws 19 are threaded to tighten the auxiliary cross bar 20 to tightly clamp the skis. If the natural longitudinal curvature of the skis suits the requirement of the user, the thumb-screws are tightened to a degree necessary to retain this curvature. If, on the other hand, it is desired to increase the curvature of the skis the thumb-screws are tightened until the required curvature is obtained. The curved offset 17 is designed to extend over the ski poles when the skis are assembled, as shown at Figures 2 and 4.

When the clamping device is not in use, the telescoped body A may be slidably contracted so that the device may be stored in a space of relatively small compass.

It is to be understood that the form of my invention herein shown and described is to be taken as a preferred example of the same and that various changes as to the shape, size and arrangement of parts may be resorted to without departing from the spirit of the invention or the scope of the subjoined claims.

Having thus described my invention, I claim:—

1. A ski clamping device comprising an elongated extensible body member, a rigid spacing member mounted transversely on the intermediate portion of the body, a rectangular shaped

clamping bracket slidably connected with each end of the body member, and means whereby the said bracket may be tightened to curve the skis relative to the transverse spacing member.

- 5 2. A ski clamping device comprising a telescopic body member, a rigid spacing member mounted transversely on the intermediate portion of the body, cross members secured to the ends of the body, a clamping bracket slidable transversely in the cross members, a clamping bar associated with and slidable on each bracket, and means on the brackets for tightening purposes.
- 10 3. A ski clamping device comprising a body

member, end members telescopically associated with the body, a cross member secured at the outer end of each end member, a yoke bracket slidable transversely in each of the cross members, a cross bar slidable in the arms of the yoke, bracket tightening means on the outer ends of the yoke arms, and a spacing member secured on the intermediate portion of the body at right angles to the longitudinal axis thereof and parallel with the longitudinal axis of the cross members and bars.

LEANDRE AUBERT.
